UNITED STATES PATENT OFFICE.

JOHN W. HASBURG, OF CHICAGO, ILLINOIS.

PAINT-PACKAGE.

1,121,357.

Specification of Letters Patent. Patented Dec. 15, 1914.

Application filed April 21, 1914. Serial No. 833,417.

To all whom it may concern:

Be it known that I, JOHN W. HASBURG, a citizen of the United States, residing at Chicago, in the county of Cook and State of Illinois, have invented certain new and useful Improvements in Paint-Packages, of which the following is a specification.

My invention relates to improvements in paint packages.

10 One of the general objects of my invention is to provide a paint package for containing paint, of a plastic nature, such as vitreous gold paint for ceramic decoration.

A more specific object of my invention is 15 to provide a paint package receptacle, similar to that disclosed in my Patent No. 1,029,926 dated June 18th, 1912, with the exception that in the present structure the palette, upon which the paint is deposited, 20 is inseparably fixed in the box in which it is contained by a retainer fixed to the box by frictional engagement therewith or otherwise, so that the transparent cover, immediately overlying the palette, must be 25 cut away and taken out of the box before the palette, upon which the paint is deposited, becomes accessible or may be removed, and furthermore the edge of the glass plate does not make actual contact 30 with the sides of the metallic box, as in my former structure, there being provided, in the present case, an intervening cushion between the edge of the glass and the metal container, to protect the former from contact with the latter. When the edges of the 35 glass palette are permitted to contact with the metal walls of the container, or inclosing box, small pieces of glass will be broken away or chipped off of the palette, and 40 these particles, as small as they may be, will ultimately find their way to the upper side of the palette and into the body of the paint, thus depreciating its quality and otherwise injuring the product.

45 Other and further objects of my invention will become readily apparent to persons skilled in the art from a consideration of the following description when taken in conjunction with the accompanying drawings, wherein—

Figure 1 is a plan view of the package, with the top removed. Fig. 2 is an enlarged transverse section taken on line 2—2 of Fig. 1, showing the top in place; and Fig. 55 3 is a sectional view showing the various parts, superposed, one upon the other, and

in their proper relative positions as they are assembled in the completed package.

In all the views the same reference characters are employed to indicate similar parts.

My package is especially designed to contain vitreous gold paint, of a plastic nature, such as used by artists for ceramic and other similar decorative work. It is highly valuable, intrinsically, and therefore must be 65 carefully preserved and protected so as to maintain it in its original state, free from deleterious influences of the atmosphere, dust and gases.

In my present invention, the paint 5 is deposited upon a glass or other vitreous palette 6. On account of the plastic nature of the paint it will stick to the palette and retain substantially its original shape or 70 configuration. It may be mixed on and used from the palette after the latter has been taken from the box, without loss or contamination. The palette 6, with a deposit of paint 5, is placed in the bottom of 75 the box 7. The box is preferably made of sheet metal, such as sheet tin, or the like, and the interior thereof is preferably coated with a coloring varnish, or the like, resembling gold, thereby affording a backing 80 for the dark brown paint deposit, visible through the palette and cover thereof, giving a warm, golden glow to the interior of the package, which produces a very artistic and pleasing effect. This feature, however, 85 is covered by a former patent and is not the subject matter of any of the claims herein.

The cover 8 is made, preferably, of a sheet of transparent celluloid and is outwardly deflected into a dome-shaped portion 9, at 90 its middle zone, to overlie the paint deposit so as not to make contact therewith. It is flat around the marginal edges of the raised dome part, as at 10, for intimate contact with the upper outlying surface of the palette. The edges are downwardly flanged, as 95 at 11. The part 11 is bent at an angle, somewhat less than 90 degrees from the horizontal portion 10, to provide an elastic cushion to protect the edges of the palette 100 from contact with the metal surface of the box. Projecting beyond the deflected portion 11 is a flange 11' for close contact with the upper surface of the bottom of the containing box. To hold the cover 8 in place I 105 provide a retainer 13, which consists of a rectangular frame, substantially the same

shape as the box 7, having a flat inturned flange 14 and a vertical part 15. The flange, or vertical wall 15, is intended to and adapted for making frictional contact with the 5 inner surface of the vertical walls of the box 7, and when it is forced into the box, after the palette has first been placed therein and the cover 7 placed over the palette, the inturned flange 14 will rest firmly upon the 10 out-turned flange 11' of the cover and hold the latter in close contact with the upper surface of the bottom of the box. The parts 11, of the cover 8, are oblique to the vertical edges of the palette and are contained between 15 said edges and the inner edges of the flanges 14 and serve as an elastic cushion to hold the palette in its position and to prevent the edges thereof from making contact with the metal portions of the box, thereby 20 preventing the edges from being chipped off to the detriment of the quality of the paint deposit.

The retainer 15 is intended to remain in the box 7 after it has been placed in position 25 at the time of assembling the parts for the package and may be soldered to the vertical wall of the box 7 or otherwise fixed thereto or its frictional contact therewith may be sufficient to maintain it in fixed position 30 without fear of displacement.

In Fig. 2 I have shown the closure 12 in place on the box, as the package will appear when it is ready for the market. When the closure, or cover 12, is removed the character 35 of the paint may be observed through the transparent covering 8 without the necessity of taking the latter from the box, but the paint cannot be used without destroying the package and therefore unauthorized interference 40 with the contents of the package cannot be effected, without substantially destroying the package. To remove the palette 6, and the cover 8 from the box, it is necessary to cut the cover between the upper 45 edge of the palette and the edge of the flange 14, with a pen knife, or other suitable instrument, to remove the cover 8 so that the palette 6 and the paint 5 may be taken from the box.

50 The vertical side edges of the box is strengthened by the three ply of metal consisting of the down turned flange of the cover 12; the upper projecting flange of the box 7, and the vertical portion 15 of the retainer, so that the surrounding side walls of the box are thus reinforced to protect the contents against damage or injury during transit.

Having thus fully described my invention, what I claim is:—

60 1. A package of the class described comprising a box; a glass palette for deposit of paint thereon within said box; a transparent

cover, overlying said palette and having a flat marginal edge in a plane with the lower 65 surface of the palette; and a retainer overlying said edge, to hold the cover and palette in place, said cover being downwardly and outwardly flared from the upper surface of the palette to the plane of the lower surface 70 of the palette to form a protecting cushion between the edge of said palette and said retainer.

2. A package of the class described comprising a box; a palette of glass for deposit 75 of paint thereon within said box; a transparent cover, having a raised dome overlying said paint and having its edges down-turned over the edge of the palette to protect said palette from contact with said box, and having a flat marginal edge and a retainer overlying said marginal edge and fixed to the box to hold the palette and cover therein.

3. A package of the class described, comprising a box; a palette of glass for deposit of paint thereon within said box; a transparent cover having a raised dome overlying said paint and having its edges down-turned over the edges of the palette, to protect said palette from contact with said box and out-turned for contact with the bottom of the box and a retainer fixed to the box bearing only on the out-turned portion of the cover to hold the palette and cover in 95 said box.

4. In a package of the class described, the combination of a box, comprising a bottom, side walls and a detachable top; a palette, of glass adapted to receive a deposit of paint, 100 positioned within said box on the bottom surface thereof with its edges spaced away from the side walls of the box; a transparent palette cover, having a raised dome overlying said paint and having its marginal 105 portions downwardly and outwardly flared from the plane of the upper surface of the palette to the plane of the bottom surface of the palette; and a retainer fixed to the side walls of the box and engaging the edges 110 of the palette cover to hold the same in close contact with the bottom of the box and thereby position the edges of the palette away from the side walls of the box, said downwardly and outwardly flaring marginal 115 portions of the palette cover forming a resilient cushion between the edges of the palette and the side walls of the box.

In testimony whereof I hereunto set my hand in the presence of two subscribing witnesses.

JOHN W. HASBURG.
